(57) **CLAIM**

The ornamental design for an cable stripping tool, as shown and described.

DESCRIPTION

FIG. 1 is a right side elevation view of a first embodiment of the cable stripping tool, the jaws of the tool being shown in a partially open position;

FIG. 2 is a left side elevation view thereof;

FIG. 3 is a front elevation view thereof;

FIG. 4 is a right side elevation view of a second embodiment of the cable stripping tool, the jaws of the tool being shown in a partially open position;

FIG. 5 is a left side elevation view thereof;

FIG. 6 is a front elevation view thereof;

FIG. 7 is an elevation view from the handle end of the cable stripping tool, the view being the same for both embodiments described above;

FIG. 8 is a top view of the tool of FIG. 1, with the jaws in the closed position, the bottom view being a mirror image thereof; and,

FIG. 9 is a top view of the toll of FIG. 4, with the jaws in the closed position, the bottom view being a mirror image thereof.

The broken lines shown on the drawings are for illustrative purposes only and form no part of the claimed design.
